UNITED STATES PATENT OFFICE.

FRANCIS W. MCQUEEN, OF FLINT, MICHIGAN, ASSIGNOR OF ONE-HALF TO LEWIS M. HENGESBAUGH, OF FLINT, MICHIGAN.

QUICK-ACTION DEVICE FOR VISES OR WRENCHES.

1,415,103.

Specification of Letters Patent. Patented May 9, 1922.

Application filed May 12, 1921. Serial No. 468,923.

To all whom it may concern:

Be it known that I, FRANCIS W. MCQUEEN, a citizen of the United States, and a resident of the city of Flint, in the county of Genesee 5 and State of Michigan, have invented certain new and useful Improvements in a Quick-Action Device for Vises or Wrenches; and I do hereby declare that the following is a full, clear, and exact description of the same, 10 reference being had to the accompanying drawings, and to the numerals of reference marked thereon, which form a part of this specification.

It is an object of this invention to provide 15 a movement for a clamp such as a vise or a wrench in which the jaws may be quickly made to approach to within very nearly the desired distance and then may be powerfully moved the remainder of their travel to that 20 distance.

It is a further object of my invention to provide such a device in which the change from slow to quick movement may be easily and readily made.

25 It is a further object of my invention to provide such a device in which the arrangement is biased towards the slow moving position.

It is a further object of my invention to 30 provide such a device which may be readily and inexpensively manufactured.

Other and further important objects of this invention will be apparent from the disclosures in the drawings and specification.

35 The invention (in a preferred form) is illustrated in the drawings and hereinafter more fully described.

On the drawings:

Figure 1 is a front view of a vise embody- 40 ing my invention.

Figure 2 is a section showing the improved part in detail.

Figure 3 is a section on the line 3-3 of 45 Figure 1.

Figure 4 is a section on the line 4-4 of Figure 1.

Figure 5 is a view of a wrench embody- 50 ing my invention.

Figure 6 is an edge view of the wrench.

Figure 7 is a sectional view on the line 7-7 of Figure 6.

Figure 8 is a section upon the line 8-8 of Figure 5.

Figure 9 is a section similar to Figure 2 showing a modification.

Figure 10 is a section on the line 10-10 of Figure 9.

As shown on the drawings:

The reference numeral 1 indicates the stationary jaw of a vise. At 2 there is pivoted to this jaw a screw 3 which works in a sleeve 4 rotated by a handle 5. This sleeve has a flange 6 and a collar 7 between which is secured a bearing collar 8. The collar 7 is secured to the sleeve 4 by any desired means 65 as driving, swaging or shrinking. The bearing collar 8 is flattened on its lower edge so that its contact with the base of the vise prevents rotation. One face of this bearing collar is beveled as shown at 9; the other 70 face is a plane perpendicular to the axis of the tube 4 and the screw 3. The bearing collar cooperates with a thrust arm 10 which has teeth, one face of which 11 is beveled to slip over the beveled face 9 of the bearing 75 collar. The opposite face 12 of these teeth is at right angles to the axis of the tube 4 and screw 3 and will fit against the plain face of the bearing collar 8. The arm 10 is pivoted at 13 to the movable jaw 14 of the 80 vise. This jaw has flanges 15 which travel in ways 16 upon the bed of the vise.

The operation of the device will be readily understood from the foregoing description. When the jaws are to be separated 85 by a considerable distance the thrust bar 10 is elevated until its teeth no longer contact with the bearing collar 8. Jaw 14 is then moved outward until the vise is opened to the desired extent. The thrust bar 10 is 90 then lowered and the bearing collar 8 will enter the notches between two of the teeth. If the edge of the bearing collar should come against the edge of the thrust bar between two teeth, the handle 5 would be turned in 95 direction to open the vise until the flat surface of the bearing collar was beyond the edge of the face 12 of the tooth. The thrust bar 10 will then fall into its illustrated position. Rotating the handle 5 in the opposite 100 direction will cause the surface of the bearing collar to press against the face 12 of the tooth and so move the jaw 14 towards the jaw 1. Thus the jaws may be quickly separated to a distance a little greater than 105 is needed to grasp any object and then

brought into grasping contact with the object by a very few rotations of the handle 5.

During the tightening of the vise the friction of the collar 8 against the face 12 of its tooth will not tilt the thrust bar 10 because this thrust bar is guided between a pair of jaws 15 upon the bearing block 17 for the sleeves 4. When the handle 5 is turned in the direction to loosen the vise the elasticity of the jaws 1 and 14 and of the object clamped between them will cause the face 12 of the tooth upon the bar 10 to follow the collar 8, but when the motion of the handle is continued in this direction the jaws will not follow more than a short distance. The collar 8 will then by its beveled surface 9 contacting with the oblique side of the teeth 11 lift the thrust bar 10, and further rotation of the handle 5 will accomplish nothing; but under these circumstances the jaw 14 is loose and may be slid by a quick motion to any desired position.

If the vise should stick, a sufficient force to start the opening movement may be had by holding the end of the thrust bar 10 between the guides 15 and turning the handle in the opening direction. The bevel of the tooth edges 11 and of the face 9 is made nearly vertical in order that no great effort shall be needed to hold the end of the bar 10 down.

Figures 9 and 10 show a modification of a vise in which the handle is applied at the other end. In these figures, the reference characters, like those already mentioned, designate the same parts as in Figures 1 to 4. Instead of applying the handle to the sleeve 4, it is in this modification applied to the screw 3. For this purpose, the jaw 1 is provided with a passage 55 through which the stem of the screw 3 extends. A collar 51 is made integral with this stem and seats in a recess 57 in the jaw 1. A collar 52 is pinned to the stem 3 at a point to contact with the other surface of the jaw 1. These two collars prevent the screw from moving lengthwise so that when the screw is turned, the sleeve 4 must travel.

The collar 8 is attached to the sleeve 4 to travel therewith as already described. Rotation of the collar 8 is prevented by its flattened side bearing against the base. A more positive holding of the collar from rotation may be secured by providing the collar with a lug 54 to travel in the groove 55 in the base. The sleeve 4 will be held from rotating by the firm grasp which the fastening 7 affords between the sleeve and the collar 8. If it is desired to positively insure that the sleeve 4 will never rotate relative to the collar 8, the two may be pinned together as is illustrated in Figure 10 at 56.

The application of this invention to a wrench is illustrated in Figures 5 to 8. In this application the jaw 21 is fixed to the

bar 23 which has upon it teeth 39 which act like threads of a screw cooperating with the rotatable nut 25. This nut has a flange 28 which has one beveled face 29 and the opposite face at right angles to the axis of the nut. A thrust bar 30 is provided with teeth having oblique edges 31 and edges 32 which extend at right angles to the axis of the ring. The thrust bar 30 is pivoted at 33 to the movable jaw 34. It is biased to the illustrated position by means of a spring 40 seated in sockets in the bar itself and in the jaw 34. The guiding member 36 is mounted upon the bar 23 just outside of the flat face of the flange 28. It has two upstanding guides 35 between which the thrust bar 30 is received. The guide 36 is constrained to move along the shaft 23 with the nut 25 by being yoked to a guide 46 which contacts with the opposite side of the nut.

The operation of the wrench is similar to the operation of the vise above described. Lifting the thrust bar 30 out of engagement with the flange 28 the movable jaw 34 may be slid along the bar 23 until a position is reached a little wider open than the size of the object to be grasped requires. The thrust bar 30 is then allowed to contact with the flange 28 in response to the spring 40. If the flange 28 does not enter exactly between two teeth as illustrated in Figure 7 the oblique surface 29 will contact with a surface 31 of a tooth. By rotating the nut in a direction to tighten the wrench the lost motion between the flat face of the flange 28 and the face 32 of the corresponding tooth may be taken up and then the jaw 34 will move in response to further rotation of the nut 25. If the lost motion to be thus taken up is too large for convenience or would bring the nut to the end of the screw formed by the teeth 39, the head 25 may be rotated a few turns in the direction to loosen the wrench, with the result that the edge of the flange 28 passes the point of a tooth and then the bar 30 in response to the spring 40 slips into the illustrated position. Thereupon the head may be rotated in the opposite direction to tighten the wrench and the flat face of the flange 28 will contact with the surface 32 of a tooth as before. In rotating the head 25 in the direction to loosen the wrench after it has grasped an object the first few turns of the head will be accompanied by an opening motion due to the elasticity of the jaws and of the object clamped. To continue rotation of the head 25 will be only to lift the bar 30 by the cam action of the oblique surface 29 adjacent the oblique surface 31. Consequently a quick motion may be substituted, by lifting the bar 30 and sliding the head 34 until the wrench is as wide open as is desired.

I am aware that numerous details of construction may be varied through a wide

range without departing from the principles of this invention, and I therefore do not purpose limiting the patent granted otherwise than necessitated by the prior art.

5 I claim as my invention:

1. In a clamping device, a fixed jaw, a movable jaw, a threaded member, a connection between said member and the fixed jaw preventing longitudinal movement of the 10 threaded member, a second threaded member rotatable relative to the first threaded member and thereby moved longitudinally of said first threaded member, a toothed member connected to the movable jaw, and means moved longitudinally of the first threaded member by the said longitudinal movement of the second threaded member and cooperating with the teeth of said toothed member to move said movable jaw when said toothed 15 member is in one position, motion of said toothed member about its pivot removing the cooperation between its teeth and said means.

2. In a quick motion clamp, clamping 25 members, a screw-driven member having two faces one toward and one away from the clamping members, the face away from the clamping members being beveled, and a thrust bar pivoted to one of the clamping 30 members and having teeth with beveled faces for cooperating with the beveled face of the screw driven member.

3. In a clamp, a fixed member, a movable member, a thrust bar pivoted to the movable 35 member, screw driven means for exerting a pressure against said thrust bar, said thrust bar being biased into a position in which it engages with said screw-driven means.

40 4. In a clamp, a fixed member, a movable

member, screw-driven means for moving said movable member toward said fixed member, said means including a separable connection, and cam surfaces acting upon rotation of the screw-driven means in the opposite direction to separate said connection. 45

5. In a clamping device, a fixed jaw, a movable jaw, a threaded member, a connection between said member and the fixed jaw preventing longitudinal movement of the 50 threaded member, a second threaded member rotatable relative to the first threaded member and thereby moved longitudinally of said first threaded member, a toothed member pivoted to the movable jaw, and means moved longitudinally of the first threaded member by the said longitudinal movement of the second threaded member and cooperating 55 with the teeth of said toothed member to move said movable jaw. 60

6. In a clamp, a movable member, a thrust bar movably connected at one end to said member, means for exerting a thrust through said thrust bar including a pair of screw-threaded members, rotational movement of 65 one of said members causing it to travel longitudinally of the other, a guide for said thrust bar at a distance from the connected end thereof said guide being stationary relative to one of said screw-threaded members 70 and the longitudinal movement of the other of said screw-threaded members causing it to move relative to said guide.

In testimony whereof I have hereunto subscribed my name in the presence of two 75 subscribing witnesses.

FRANCIS W. McQUEEN.
